Attorney

UNITED STATES PATENT OFFICE.

DAVID ROY WHITE, OF CHICAGO, ILLINOIS.

PLANT-IRRIGATING DEVICE.

1,342,786.

Specification of Letters Patent.

Patented June 8, 1920.

Application filed December 14, 1918. Serial No. 266,717.

To all whom it may concern:

Be it known that I, DAVID ROY WHITE, a citizen of the United States, residing at Chicago, in the county of Cook and State 5 of Illinois, have invented certain new and useful Improvements in Plant-Irrigating Devices, of which the following is a specification.

This invention relates to plant irrigating 10 devices and has for its primary object to improve the construction and increase the efficiency of devices of the character shown and described in my prior Patent No. 1,216,642, issued February 20, 1917.

15 It is a more particular object of the invention to provide very simple and reliable means for automatically supplying moisture by capillary attraction to the earth in a flower pot adjacent to the roots of the plant.

20 In detail the invention consists in an improved supporting base for the flower pot having a top wall provided with an opening, said base constituting a water receiving chamber, and absorbent means extending 25 into the water chamber and having a disk-like mat disposed upon said top wall and upon which the pot is immediately supported.

It is also a further general object of my 30 invention to provide a device for the above purpose which is very durably constructed and may be manufactured and sold at relatively small cost.

Having the aforementioned objects in 35 mind, the present invention comprehends certain novel and improved combinations of elements and the structural characteristics thereof as will be more fully developed in the following description and subsequently 40 incorporated in the subjoined claim.

In the accompanying drawing, wherein similar reference characters designate corresponding parts throughout the several views;

45 Figure 1 is a perspective view illustrating the preferred embodiment of my improved plant irrigating device.

Fig. 2 is a vertical sectional view.

Referring in detail to the drawing 5 designates the body section of the pot supporting base and 6 the top section thereof. These base sections are preferably formed of stamped sheet metal and the inclined annular wall of the body section is vertically 55 extended at its upper edge to form a clamp-

ing flange 7, the purpose of which will presently appear.

The top section 6 consists of a single metal sheet stamped or pressed to form a wall 8 constituting the top of the water receiving chamber 9. At the outer edge of this wall the vertical flange 10 is formed and the lateral flange 11 extending outwardly from said vertical flange. The edge of the flange 11 is downwardly and inwardly turned to provide a reinforcing bead 12.

The wall 8 is formed with a central opening 13 and additional diametrically opposed openings 14 adjacent to its outer edge.

In assembling the base sections the flange 10 of the top section is forced downwardly within the annular flange 7 of the body section and said latter flange is thereby sprung outwardly and caused to tightly clamp or grip against the outer face of the flange 10. 70 The parts are thus securely held in assembled relation and the possibility of their relative accidental displacement obviated.

The chamber 9 is supplied with water 80 through the openings 14, and within this chamber a piece of sponge or other suitable absorbent material is disposed, as shown at 15. An end of the sponge is extended through the central opening 13 and to the same a disk-like mat of burlap or other 85 porous, absorbent material is tied or otherwise conveniently secured. This mat, indicated at 16, is preferably, though not necessarily, of circular form and of such diameter that it will not cover the openings 14. 90 The flower pot, shown at P, is immediately supported upon the mat 16 and is provided in its bottom wall with the usual opening P'.

In the practical operation of the device, 95 it will be understood that the water is absorbed by the sponge and also thoroughly saturates the fibers of the mat 16. Thus, by capillary attraction, the water is drawn upwardly and the moisture is disseminated 100 through the earth in the pot which surrounds the roots of the plant. In this manner a copious supply of moisture to the plant roots is automatically maintained and the growth of the plant to full maturity 105 greatly facilitated, without necessitating frequent care and attention. Any excess of water will collect upon the wall 8 and drain back into the chamber 9 through the openings 14, the flange 10 effectually preventing 110

the escape of such water over the edge of the supporting base.

It will be understood that the sponge, as it absorbs the water, swells or expands 5 to a diameter greatly in excess of the diameter of the opening 13. Therefore, the mat 16 will be held against displacement in the event it should adhere to the pot when the latter is lifted. Also the water chamber 10 may be inverted to empty the contents thereof without detachment of the water conducting means.

From the foregoing it is believed that the construction, manner of operation and 15 several advantages of the invention will be fully and clearly understood. It will be appreciated that I have materially simplified the construction of my prior invention and at the same time increase its efficiency, 20 serviceability, and convenience in practical use. The improved device may also be manufactured at considerably less cost than the patented invention above referred to. While I have herein referred to the device 25 as constructed of sheet metal it is manifest that it may also be formed of clay or other refractory materials, if desired.

In the preceding description and accom-

panying drawing I have disclosed one practical embodiment of the invention, which, 30 however, may likewise be exemplified in numerous other alternative constructions. Accordingly, the invention as herein claimed is to be considered as inclusive of all legitimate equivalents for the various elements 35 employed as well as other contemplated arrangements thereof, which may satisfactorily accomplish the desired results.

What I claim is:—

An irrigating device for plants including a water receiving chamber having a body section and a top section, the latter section being formed with an annular flange fitting within said body section and engaged by the wall thereof, the top section being 40 centrally formed with an opening and additional diametrically opposed openings, an absorbent mat disposed upon said top section over the central opening and between the additional openings and upon which a 45 potted plant is adapted to be immediately supported, and water conducting means connected to said mat and extending into said chamber.

In testimony whereof I affix my signature. 50
DAVID ROY WHITE. 55
